UNITED STATES PATENT OFFICE.

HAROLD MACDOUGALL, OF MAPLEWOOD, NEW JERSEY.

VANITY CASE.

Application filed May 1, 1926. Serial No. 106,146.

This invention has relation to dispensing containers and has particular reference to a container for use as a vanity case to constitute a convenient, safe, and sanitary means

5 for carrying, dispensing and applying loose face powder.

Primarily the invention comprehends a vanity case constituting a dispensing container for loose powder in which the applicator or puff elements is connected with the container and in which means is provided for dispensing the contents through the puff or applicator member on to its applying face.

10 More specifically, the invention contemplates a dispensing container for face powder or other powdered substances, which consists of a hollow, open-ended body closed at one end by a flexing wall constituting means when flexed inwardly for creating a pressure within the body and having a porous applicator or puff member provided with an outer applying face arranged over the open end and through which the powdered contents is dispensed on to the outer applying face when the flexing end of the body is flexed inwardly to create an internal pressure.

15 The invention furthermore contemplates means for detachably associating the puff or applicator member with an open end of the container body whereby said puff or applicator member may be periodically renewed and whereby means is afforded for introducing the contents to the body.

20 A further object of the invention resides in the provision of means for removably retaining the applicator or puff element in associated relation with the container body, which means also constitutes a seat for a cover for housing and protecting the applicator element.

25 The invention furthermore aims to provide a device of the character set forth, which is comparatively simple in its construction and mode of use, which is inexpensive to manufacture, and which is highly efficient in its purpose.

With the above recited and other objects 30 in view, reference is had to the following specification and accompanying drawings in which there is exhibited one example or embodiment of the invention which is in no way intended as a limitation upon the scope of 35 the appended claims as it is to be clearly

understood that variations and modifications which properly fall within the scope of said claims may be resorted to when found expedient.

60 In the drawings—

Figure 1 is a perspective view of the case in closed condition;

Fig. 2 is a vertical sectional view therethrough;

Fig. 3 is a collective perspective view of 65 the elements or parts in disassembled condition.

Referring to the drawings by characters of reference, 10 designates a hollow, preferably cylindrical, body, which is closed at its 70 lower end by a flexing end wall 11 normally bulged or flexed outwardly due to its inherent resiliency, which wall is preferably connected by an annulus 12 to the lower end of the body 10. In order to limit the inward 75 flexing and to insure a normal outward flexing of the wall 11, a ring 13 is provided which is formed with radial inwardly projecting fingers 14, said ring being clamped between the margin of the wall 11 and the annulus 80 12. The body 10 is provided with an upper portion 15 of relatively reduced diameter forming an annular shoulder 16, the upper end being open. A puff or applicator member 85 including a porous body 17 provided on its outer side with a nap 18 constituting an applying face, is provided, which is stretched or arranged over the open end of the body 10. The means for removably stretching and retaining the applicator member over the open end consists of a frictional clamping ring 19 which is of an appropriate size to snugly fit around the downturned margin of the applicator member and arranged over the reduced upper portion 15. 90

The clamping ring is provided at its lower end with a marginal or peripheral bead 20, which in addition to serving as means for facilitating its removal also constitutes a stop or abutment for the marginal depending flange 21 of a cover 22, which carries a mirror 23 clamped between the bead 24 at the upper end of the flange 21 and the end wall 25 of the cover.

100 In use, the loose face powder or other substance to be dispensed and applied, is arranged within the body 10, and after the applicator or puff element is arranged and clamped in place by stretching the same over the upper open end of the body, the clamp 110

ing ring is engaged thereover as illustrated. By flexing the lower end 11 inwardly, an internal pressure is created which dispenses through the porous body 17 on to the nap or applying face 18, a quantity of the contents. The fingers 14 of the ring 13 serve as a means for limiting the inward movement and insure the return of the end wall 11 to a normal outwardly flexed position when manual pressure thereon is discontinued. The user then employs the body 10 as a holder or handle for applying the powder-laden applying face 18 to the point at which the powder is to be applied. The cover 22 serves as a means for normally housing and protecting the applicator member and when removed the same serves in the capacity of a mirror.

What is claimed is:

1. A dispensing container for powdered substances, comprising a hollow open-ended body having a flexing portion constituting means when flexed inwardly for producing an internal pressure within the body, and a porous applicator member having an outer applying face arranged on said open end of the body through which the powdered contents is dispensed on the outer applying face when the flexing portion of the body is flexed inwardly.

2. A dispensing container for powdered substances, comprising a hollow, open-ended body having a flexing portion constituting means when flexed inwardly for producing an internal pressure within the body, a porous applicator member having an outer applying face arranged on said open end of the body through which the powdered contents is dispensed on to the outer applying face when the flexing portion of the body is flexed inwardly, said porous applicator member being of a flexible material, and means engaging over the marginal edge of the applicator and open end of the body for clamping the same in stretched relation over said open end.

3. A dispensing container for powdered substances, comprising a hollow, open-ended body having a flexing portion constituting means when flexed inwardly for producing an internal pressure within the body, a porous applicator member having an outer applying face arranged on said open end of the body through which the powdered contents is dispensed on to the outer applying face when the flexing portion of the body is flexed inwardly, said porous applicator member being of a flexible material, means engaging over the marginal edge of the ap-

plicator and the open end of the body for clamping the same in stretched relation over said open end, and a cover for said applicator.

4. A dispensing container for powdered substances, comprising a hollow, open-ended body having a flexing portion constituting means when flexed inwardly for producing an internal pressure within the body, a porous applicator member having an outer applying face arranged on said open end of the body through which the powdered contents is dispensed on to the outer applying face when the flexing portion of the body is flexed inwardly, said porous applicator member being of a flexible material, means engaging over the marginal edge of the applicator member and the open end of the body for clamping the same in stretched relation over said open end, a cover for said applicator member, and retaining means for detachably associating the applicator member with the body.

5. A dispensing container for powdered substances, comprising a hollow, open-ended body having a closed flexing end constituting means when flexed inwardly for producing an internal pressure within the body, a porous applicator member having an outer applying face arranged on said open end of the body through which the powdered contents is dispensed on to the outer applying face when the flexing end of the body is flexed inwardly, said porous applicator member being of a flexible material, means engaging over the marginal edge of the applicator member and the open end of the body for clamping the same in stretched relation over said open end, a cover for said applicator, and retaining means for detachably associating the applicator member with the body, said retaining means constituting a seat for the cover.

6. A dispensing container for powdered substances, comprising a hollow, open-ended body having a closed flexing end constituting means when flexed inwardly for producing an internal pressure within the body, a porous applicator member having an outer applying face arranged on said open end of the body through which the powdered contents is dispensed on the outer applying face when the flexing end of the body is flexed inwardly, and means within the closed flexing end for limiting the inward flexing thereof and for insuring a normal outward flexing of the same when inward pressure thereon is discontinued.

HAROLD MACDOUGALL.
